tion, a corporation of Delaware

Application June 20, 1942, Serial No. 447,757

9 Claims. (Cl. 178—7.5)

This invention relates to a projection tube and more particularly to a control arrangement in such a tube which employs the storage principle.

In projection tubes of this type, there is generally provided an unmodulated source of electrons, which electrons are controlled in accordance with stored electrical charges. These stored electrical charges are developed by means of an electron beam which is modulated in accordance with received picture signals. In this way, the picture signals are effective in controlling the unmodulated source of electrons for an extended interval of time, such as the scanning line period or a field or frame period. The electrons controlled in this manner are utilized to produce a luminescent effect, the duration of which is obviously longer than the time interval allotted to the scanning of a single picture element. In this manner, a picture of increased brilliance is produced.

In conventional projection tubes of the type described, a charge image having the dimensions of the scanning line or of a complete picture is developed by means of a scanning beam modulated by picture signals. Obviously, a charge developed on an elemental area of the charge image must be neutralized before the scanning beam returns to this area to develop a new charge thereon after a line, field or frame interval. In some types of tubes in the prior art, the charges forming the charge image are permitted to leak away in accordance with an exponential function during the scanning period. Obviously, this is an inefficient method of operation since the luminescence produced by the controlled electrons also decays according to an exponential function instead of maintaining its maximum value throughout the scanning period. Arrangements have been proposed in which this defect is supposed to be overcome by employing a second scanning beam which neutralizes the charges of the charge image shortly before new charges are created by the first scanning beam. Such arrangements, however, have generally been found to be difficult to construct or to operate.

It is an object of the present invention, therefore, to provide a new and improved projection tube incorporating an electron control arrangement of simple construction and increased efficiency.

In accordance with the present invention, there is provided a cathode ray projection tube having a uniform source of electrons. A plurality of mutually insulated charge storage elements are po-

sitioned adjacent the uniform source of electrons for controlling the emission of the electrons therefrom in accordance with the individual charges on the elements. Means are also provided for producing an unmodulated beam of electrons and for deflecting the beam across the charge storage elements to liberate secondary electrons therefrom to produce charges thereon. A collector is provided for collecting the secondary electrons. Means are provided for varying the potential of the collector in accordance with picture signals so that the charges on the charge storage elements are controlled thereby. Finally, a target means is provided and means for directing the controlled electrons from the uniform source onto the target means to produce a luminescent effect.

For a better understanding of the invention, together with other and further objects thereof, reference is had to the following description, taken in connection with the accompanying drawing, and its scope will be pointed out in the appended claims.

In the accompanying drawing,

Fig. 1 is a diagrammatic sectional view of a projection tube in accordance with the invention; and

Fig. 2 is a perspective view of a control arrangement embodying the invention and incorporated in the projection tube illustrated in Fig. 1.

Referring now more particularly to Fig. 1 of the drawing, there is shown a diagrammatic sectional view of a projection tube having an envelope comprising a main cylindrical portion 11 and a neck portion 12. At one end of the main cylindrical portion 11, there is provided a linear cathode 13, preferably of the type that is indirectly heated, for producing a uniform source of electrons. The source of energy for making the cathode electron-emissive is provided by a battery 14. The cathode 13 is positioned in a recess 16 of a supporting body 17, preferably of metal. Upon the supporting body 17, there is positioned a plurality of grid elements or wires 18 adjacent to each other. The grid elements 18 are insulated in a suitable manner from each other and from the supporting body 17 and will be referred to in greater detail hereafter.

In the neck portion 12, there is provided an electron gun for producing an unmodulated beam of electrons. The electron gun comprises a cathode 20, a control element or grid 22, and an accelerating anode 23. The cathode 20, the grid 22 and the anode 23 may be operated at progressively increasing potentials, as shown in

Fig. 1, or the grid 22 may be at a potential negative with respect to the potential of the cathode 20. The cathode 20 is energized by a battery 24 to a potential substantially below ground. The electron beam is focused by a magnetic focusing coil 25 of the conventional type, which is connected in series with a battery 26 and a variable resistor 27.

The electron beam is deflected across the charge storage elements 18 by a pair of deflecting plates 28 energized by a generator 29 capable of producing a saw-tooth voltage of line or first frequency. In Fig. 1, this sweep would occur perpendicular to the face of the drawing.

A pair of metal members 31, preferably L-shaped and conductively connected together, are positioned adjacent the portions of the elements 18 which are impacted by the beam of electrons. From the terminal 32, a picture signal is fed through a blocking condenser 33, which is of negligible impedance to the frequencies involved; and the picture signal appears as potential variation at the members 31, over the resistor 34. The members 31 constitute a collector for collecting secondary electrons emitted from the elements 18, in proportion to the strength of the picture signal.

The end of the main tube portion 11 remote from the control elements 18 is provided with a target means 36. Preferably, the target means 36 is a layer of fluorescent material deposited on the inner vertical wall at the end of the main tube portion 11. The electrons from the cathode 13, controlled by the charges on the elements 18, are accelerated toward the target 36 by an electrode 37. Preferably, the electrode 37 is a coating on the interior of the main portion 11 of the envelope, as shown in Fig. 1, and is energized by a battery 38. A magnetic focusing coil 39, connected in series relationship with a battery 40 and a variable resistor 41 is provided in the conventional manner to focus the electron image of the controlled emission from the cathode 13 onto the target 36. Where the cathode 13 is linear in form, as illustrated in the drawing, the electron image represents one scanning line. A pair of deflecting coils 42, which are fed by a scanning frequency generator 43, operating at a frame or second frequency, are provided for deflecting the electron image in a vertical direction across the target 36.

Fig. 2 shows a perspective view of the control arrangement described above. One method of building this control arrangement is to wind many turns of fine wire around the supporting body 17. Preferably, several turns of the wire per unit cathode length correspond to a picture element. The wires are insulated from the supporting body 17 in a suitable manner. They are also insulated from each other by being separated from each other and being cut at the recess 44 in the body 17.

In operation of the projection tube, a high-velocity electron beam is produced by the electron gun comprising the cathode 20, the control element 22 and the anode 23. The electron beam is of uniform intensity and is deflected across the elements 18 at line frequency to release secondary electrons therefrom. A portion of the secondary electrons is collected by the collector members 31 in accordance with the instantaneous potential thereof which is controlled by the picture signals applied thereto, as described above. As is well known, an insulated member which is bombarded by high-velocity electrons and emits

secondary electrons tends to approach the potential of an adjacent collector of the secondary electrons. In this manner, the number of secondary electrons emitted by the successive elements 18 under bombardment of the scanning beam varies in accordance with the picture signals applied to the collector members 31 and, hence, a charge image corresponding to a single scanning line is produced on the elements 18 which controls the emission from the linear cathode 13. Once, one of the grid elements 18 has acquired a certain charge and potential, it retains the same over a relatively long period of time since it is perfectly insulated from the supporting body 17. The potential is not appreciably influenced during the rest of the line scanning cycle by subsequent changes in the potential of the collector members 31. Obviously, therefore, the control effect of the elements 18 and the luminescence produced by the electrons from the cathode 13 remain constant until the scanning beam is ready to scan the control elements again. During the re-scanning, the potential of the collector is varied by the picture signals from its previous value. Thus, new charges and new control potentials are established on the same control element during each cycle of line scanning.

During the scanning of the elements 18 by the electron beam, the deflecting field generated by the coils 42 changes continually to place successive luminescent lines of an image on the target 36.

It will be apparent from the above description that such operation greatly increases the efficiency of a projection tube while still providing a simple construction thereof.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A cathode ray projection tube having a uniform source of electrons, a plurality of mutually insulated charge storage elements positioned adjacent said uniform source of electrons for controlling the emission of electrons therefrom in accordance with the individual charges on said elements, means for producing an unmodulated beam of electrons, means for deflecting said beam across said elements to liberate secondary electrons therefrom to produce charges thereon, a collector for collecting said secondary electrons, means for varying the potential of said collector in accordance with picture signals, thereby to control the charges on said elements, a luminescent target means, and means for directing the electrons from said uniform source onto said target means to produce a luminescent effect.

2. A cathode ray projection tube having a uniform source of electrons, a plurality of mutually insulated charge storage elements positioned adjacent said uniform source of electrons for controlling the emission of electrons therefrom in accordance with the individual charges on said elements, means for producing an unmodulated beam of electrons, means for deflecting said beam across said elements to liberate secondary electrons therefrom to produce charges thereon, a collector for collecting said secondary

electrons, means for varying the potential of said collector in accordance with picture signals, thereby to control the charges on said elements, a luminescent target means, means for directing the electrons from said uniform source onto said target means, and means for deflecting the electrons from said uniform source across said target means to produce a luminescent effect.

3. A cathode ray projection tube having a uniform source of electrons, a plurality of mutually insulated charge storage elements positioned adjacent said uniform source of electrons for controlling the emission of electrons therefrom in accordance with the individual charges on said elements, means for producing an unmodulated beam of electrons, means for deflecting at a first frequency said beam across said storage elements to liberate secondary electrons therefrom to produce charges thereon, a collector for collecting said secondary electrons, means for varying the potential of said collector in accordance with picture signals, thereby to control the charges on said elements, a luminescent target means, means for directing the electrons from said uniform source onto said target means, and means for deflecting at a second frequency the electrons from said uniform source across said target means to produce a picture.

4. A cathode ray projection tube having a linear cathode for producing a uniform source of electrons, a plurality of mutually insulated charge storage elements positioned adjacent said linear cathode for controlling the emission of electrons therefrom in accordance with the individual charges on said elements, means for producing an unmodulated beam of electrons, means for deflecting said beam across said storage elements to liberate secondary electrons therefrom to produce a linear charge pattern thereon, a collector for collecting said secondary electrons, means for varying the potential of said collector in accordance with picture signals, thereby to control the charges on said elements, a luminescent target means, means for directing the electrons from said uniform source onto said target means, and means for deflecting the electrons from said linear cathode across said target means to produce a picture.

5. A cathode ray projection tube having a uniform source of electrons, a plurality of mutually insulated charge storage elements positioned adjacent said uniform source of electrons for controlling the electrons therefrom in accordance with the charge on said elements, means for producing an unmodulated beam of electrons, means for deflecting said beam across said elements to liberate secondary electrons therefrom to produce charges thereon, a pair of angularly shaped electrodes for collecting said secondary electrons, means for varying the potential of said electrodes in accordance with picture signals, a luminescent target means, and means for directing electrons from said uniform source onto said target means to produce a luminescent effect.

6. A cathode ray projection tube having a uniform source of electrons, a plurality of mutually insulated charge storage elements positioned adjacent said uniform source of electrons for controlling the electrons therefrom in accordance with the charge on said elements, an electron gun for producing an unmodulated beam of electrons, means for deflecting said beam across said elements to liberate secondary electrons therefrom to produce charges thereon, a collector for collecting said secondary electrons, means for varying the potential of said collector in accordance with picture signals, a luminescent target means, and means for directing electrons from said uniform source onto said target means to produce a luminescent effect.

10 7. A cathode ray projection tube having a uniform source of electrons, a plurality of mutually insulated charge storage elements positioned adjacent said uniform source of electrons for controlling the emission of electrons therefrom in accordance with the individual charges on said elements, means for producing an unmodulated beam of electrons, means for directing said beam

15 of electrons in a first direction toward said elements, means for deflecting said beam across said elements to liberate secondary electrons therefrom to produce charges thereon, a collector for collecting said secondary electrons, means for varying the potential of said collector in accordance with picture signals, thereby to control the charges on said elements, a luminescent target means, and means for directing electrons from said uniform source onto said target means to produce a luminescent effect.

20 8. The method of producing an image on a recording surface which comprises the steps of producing a uniform stream of electrons, controlling said stream of electrons by a charge image in the path of said stream of electrons, utilizing an unmodulated beam of electrons to liberate secondary electrons, collecting liberated secondary electrons in accordance with image signals to vary said charge image, and directing said controlled stream of electrons onto said recording surface for producing a luminescent effect thereon.

25 9. The method of producing an image on a recording surface which comprises the steps of producing a linear uniform stream of electrons, controlling said stream of electrons by a charge image in the path of said stream of electrons,

30 utilizing an unmodulated beam of electrons, means for deflecting said beam across said elements to liberate secondary electrons therefrom to produce charges thereon, a collector for collecting said secondary electrons, means for varying the potential of said collector in accordance with picture signals, thereby to control the charges on said elements, a luminescent target means, and means for directing electrons from said uniform source onto said target means to produce a luminescent effect.

35 10 8. The method of producing an image on a recording surface which comprises the steps of producing a uniform stream of electrons, controlling said stream of electrons by a charge image in the path of said stream of electrons, utilizing an unmodulated beam of electrons to liberate secondary electrons, collecting liberated secondary electrons in accordance with image signals to vary the said charge image, and deflecting said controlled stream of electrons onto said recording surface for producing a luminescent effect thereon.

35 9. The method of producing an image on a recording surface which comprises the steps of producing a linear uniform stream of electrons, controlling said stream of electrons by a charge image in the path of said stream of electrons,

40 utilizing an unmodulated beam of electrons, means for deflecting said beam across said elements to liberate secondary electrons therefrom to produce charges thereon, a collector for collecting said secondary electrons, means for varying the potential of said collector in accordance with picture signals, thereby to control the charges on said elements, a luminescent target means, and means for directing electrons from said uniform source onto said target means to produce a luminescent effect.

45 10 8. The method of producing an image on a recording surface which comprises the steps of producing a uniform stream of electrons, controlling said stream of electrons by a charge image in the path of said stream of electrons, utilizing an unmodulated beam of electrons to liberate secondary electrons, collecting liberated secondary electrons in accordance with image signals to vary the said charge image, and deflecting said controlled stream of electrons onto said recording surface for producing a luminescent effect thereon.
